UNITED STATES PATENT OFFICE.

MARCUS PHILLIPS, OF CHICAGO, ILLINOIS.

CURTAIN-STRETCHER.

1,216,725.

Specification of Letters Patent. Patented Feb. 20, 1917.

Application filed March 15, 1915. Serial No. 14,320.

To all whom it may concern:

Be it known that I, MARCUS PHILLIPS, a citizen of the United States, residing at Chicago, in the county of Cook and State of Illinois, have invented new and useful Improvements in Curtain-Stretchers, of which the following is a specification, reference being had to the accompanying drawings, forming a part thereof.

10 The purpose of this invention is to provide an improved device, particularly adapted for the purpose of stretching lace curtains, or other like articles, for drying, but adapted for other uses such as quilting frames and the like. It consists in the elements and features of construction shown and described as indicated in the claims.

In the drawings:

Figure 1 is a perspective view of a structure embodying this invention.

Fig. 2 is a detail plan view of two engaged members at one intersection or corner of the frame.

Fig. 3 is a section at the line, 3—3 on Fig. 2.

Fig. 4 is a detail plan of adjacent portions of two bars with connecting clamp member removed.

Curtain stretching frames and like structures in common use have generally been made with the intersecting bars crossing each other, one lapped upon the other, that is to say, so that two opposite side bars are lapped upon top of two other opposite side bars, the end portions of each of the crossing or intersecting bars extending outward beyond their intersections as to any excess of length not in use for bounding the area of the curtain to be stretched upon the frame.

40 The construction locating two opposite bars in a different plane from the other two opposite bars intersecting the first, is seriously objectionable, because it results in stretching the curtain unnaturally at the corners and 45 distorting the corners because the two edges forming the corner are drawn and fastened in different planes. The structure shown in the drawings comprises four bars, all of which are precisely alike in formation, each 50 bar, A, having at one end only a metal loop, B, forming an eye or opening b, for receiving the other or plain end of the adjacent bar in the same plane with the bar having

the loop. All the four corners of the frame are just alike, the plain end of one bar being inserted through the loop of the other end of the other bar, and projected past the loop-carrying end of said other bar to the amount of any excess of the length of the bar over the dimension of the frame required for the curtain to be stretched. Such frames are usually rectangular, and to insure the bars being secured together at adjusted dimensions of the frame perfectly at right angles to each other, the clamping of each bar in the loop to which it is inserted on the adjacent bar, is effected by a clamp screw, C, set in through the end of the loop for acting against the edge of the bar which extends through the loop, that is, for pressing it toward the end of the other bar in the plane of the frame. The end of the bar having the loop forms the inner side of the eye bounded by the loop, and the two opposite corners of this end being in a line at right angles to the length of the bar, the end of the bar being either cut directly square across or hollowed between the corners as suggested by dotted line, A^x, and the clamp screw, C, being opposite a point intermediate the corners, the tightening of the clamp screw sets the bar which is inserted through the loop up against the end of the other bar squarely at right angles thereto. To prevent the clamp screw from scoring or marking the edge of the bar inserted through the loop, there is provided a spring shoe, D, which is a strip of metal secured on the inside of the loop to mask the inner end of the screw when it is tightened against the cross-bar. The free end of this strip is bent over to engage the side of the square nut on the clamp screw, C, thus stopping the nut against rotation. Preferably the spring, D, is also bent down at the opposite side of the nut so that when the clamp screw, C, is removed, the spring, D, and the sides of the loop, B, form a housing to retain the nut in position.

The various methods which have been commonly employed for securing the curtain to the bars of the frame, are open to different objections. When common tenter hooks or hooks of like character are provided upon the bars they become damaged and bent out of place when the bars are

stored away and make them very inconvenient to handle in mounting, because the tenter hooks must be quite sharp in order to avoid injuring the fabric when it is stretched upon them, and the bars thus become somewhat dangerous in handling. In other forms of frame in common use the bars are furnished with a covering of fabric for pinning the curtain to the bars; but in using frames of this character, the pins very frequently strike the wood when pinning the curtain to the fabric, and the thumb and fingers of the operator frequently become chafed to bleeding by the time the curtain has been pinned in place. These defects of prior constructions are avoided by providing the bar, A, with obliquely-inward-trending pin-holes, a^2 , preferably at uniform distances, as for example, one inch, apart along the whole length of the bars. The operator has only to draw the edge of the curtain over the edge of the bar and insert a pin through the fabric and into the hole nearest the corner in each of the bars at the corner, then continuing along either edge, suitably stretching the edge and inserting a pin through the fabric and into the next pin-hole, which will be clearly in sight so as to receive the pin without any snagging by catching its point in the wood which would tend to bruise the fingers of the operator by the head of the pin. The pin being inserted obliquely downward and inward so that the projecting portion projects obliquely upward and outward, the stretching of the curtain draws it down into the acute angle between the pin and the surface of the bar, and obviates any liability of bending the pin by the stretching of the curtain, and in fact with pins of toilet size, as many as half a dozen curtains may be stretched at a time upon the frames constructed as provided in this manner. For convenience in entering the pin into the pin-hole, the surface of the bar has a longitudinal groove, a^2 , crossing the mouths of all the pin-holes,—that is, all the pin-holes start at this groove, so that the operator, even having dim sight or trembling hands, can readily direct the pin into the pin-hole by merely drawing the point on the surface of the bar to the groove and then along the groove to the pin-hole. For a like purpose, as well as to render each bar available as a measuring rod for stretching the curtain to exact dimensions, transverse grooves, a^3 , are formed on the surface of the bar from each pin-hole inward to the inner edge and outward for a sufficient distance toward the outer edge of the bar to be seen beyond the edge of the curtain when pinned in place on the bar. In assembling the bars and clamping them together, the longitudinal groove, a^2 , being registered within a transverse groove, a^3 , will locate a pin-hole exactly at the corner of the curtain which is

desirable, and all the corners being thus adjusted, the frame will be adapted to stretch the curtain in each dimension to exactly a selected number of inches.

It is desirable that a frame for this purpose should be self-supporting, both for convenience of stretching the curtain on the frame and also for advantage in drying the curtains on the frame, and for this purpose there are provided legs, E, which may be comparatively slender rods, and for securing them at the corners of the frame the loop fittings, B, have holes b^4 , registering with holes in the bars, A, through which screws, F, are inserted from the top and screwed down into the ends of the legs. Suitably long and large threaded screws being employed, and holes being first bored in the ends of the legs for them of suitable size to permit the screws to cut their own threads permanently in the wood, the screws may be withdrawn when the frame is disassembled for storage, and re-inserted indefinitely without wearing out their hold upon the wood.

90 I claim:—

1. A curtain stretcher comprising bars, each having one end provided with a metal loop through which the other end of the adjacent cross-bar can be thrust, and means for clamping such cross-bar in said loop comprising a clamp screw loosely inserted through the end of the loop; a non-circular nut on said screw inside the loop, and a spring shoe secured to the loop and extending between the end of the screw and the edge of the bar to be clamped therein, said shoe being formed to engage also the non-circular edge of the nut.

105 2. A curtain stretcher comprising bars each having one end provided with a flat metal loop through which the other end of the adjacent cross-bar can be thrust to form a rectangular frame, and means for clamping said cross-bar in such loop comprising a clamp screw loosely inserted through the end of the loop; a non-circular nut on said screw within the loop and dimensioned to be engaged by the opposing walls of said loop and thereby stopped against rotation, 110 and a spring shoe disposed between the end of said clamp screw and the member to be clamped, and having portions bent to extend past those sides of the nut facing the open sides of the loop for positioning the 115 nut independently of the clamp screw.

3. In a curtain stretcher comprising frame bars each having at one end a metal loop for the insertion of an adjacent cross-bar in the same plane with the bar having the loop, the loop fitting comprising flat portions extending over the top and bottom surfaces of the bar for securement thereto, said portions having vertically registered apertures; a leg member having a threaded bore in 120 125 130

one end and an attaching screw extending through the said apertures of the loop fitting and into said threaded bore of the leg for removably securing the upper end of the latter against the flat under side of the loop fitting.

In testimony whereof, I have hereunto set

my hand at Chicago, Illinois, this 8th day of March, 1915.

MARCUS PHILLIPS.
